APPARATUS FOR SEPARATING LIQUIDS OF DIFFERENT SPECIFIC GRAVITY

Filed Jan. 14, 1925

Fig. 1.

Fig. 5.

UNITED STATES PATENT OFFICE.

THOMAS FISHER, OF PHILADELPHIA, PENNSYLVANIA, ASSIGNOR TO FISHER ENGINEERING CORPORATION, OF BALTIMORE, MARYLAND, A CORPORATION OF MARYLAND.

APPARATUS FOR SEPARATING LIQUIDS OF DIFFERENT SPECIFIC GRAVITY.

Application filed January 14, 1925. Serial No. 2,382.

The object of my invention is to improve the construction of an apparatus for separating liquids of different specific gravity, particularly water from oils or other liquids 5 lighter than water, and separate heavier particles from the water and oil prior to the separation of the water from the oil.

A further object of the invention is to construct the apparatus so as to raise the 10 level of the separated oil, by reducing the area of that portion of the apparatus, in which the separated oil is located.

The invention also relates to details of construction, which will be fully described 15 hereinafter.

While the invention is particularly adapted for separating oil from water or water from oil, it will be understood that it can be used for separating other liquids of different specific gravity, without departing from 20 the essential features of the invention.

In the accompanying drawings:

Fig. 1 is a vertical sectional view of my improved apparatus for separating water 25 from oil;

Fig. 2 is a sectional plan view on the line 2—2, Fig. 1;

Fig. 3 is a side view of a portion of Fig. 1, with the outer casing in section;

Fig. 4 is a detached view of the steam coil; and

Fig. 5 is a longitudinal sectional view of the tank, in which the heavy particles are separated from the water and oil.

The outer casing 1 can be of any height and diameter desired. A casing 2 is located within the outer casing and is spaced therefrom to form a channel 3, in which is a helical deflector 4. This deflector terminates at the upper end in a vertical section 4^a, which extends past the inlet opening 5 for the water and oil. The inlet opening is on that side of the deflector that allows the water and oil to travel over the inclined surface of 45 the deflector.

As the water passes down the channel 3, the oil accumulates on the under side of the deflector, which is inclined. This oil travels up the inclined surface to the oil zone 6 of the apparatus. The oil is separated from the incoming oil and water by the vertical section 4^a of the deflector.

This construction is fully described in the pending application for patent filed by me

on the 28th day of February, 1924, under 55 Serial No. 695,821.

In order to reduce the area of the oil zone 6, a casing 7 is provided, which is secured to the inner casing 2 in any suitable manner. The under side of the casing 7 is preferably 60 beveled, as shown, to allow oil to pass readily to the oil zone. The casing 7 is preferably filled with concrete, or other suitable material, and a space 8 is provided directly opposite the oil discharge pipe 9 to allow for 65 the free flow of oil to the outlet. In the oil zone is a steam pipe 10. The steam heats the oil so that it flows freely from the apparatus. The pipe is coiled, preferably in the manner shown in Fig. 4, leaving a free 70 space at the center for the passage of oil into the space 8, as shown clearly in Fig. 2.

By reducing the diameter of the apparatus at the oil zone, the level of the oil is raised 75 so that there is a considerable distance between the water level *x* and the oil level *y*. Within the inner casing 2 is an outlet pipe 11 for the water that has been separated from the oil. This outlet pipe communicates with a waste water pipe 12 at the bottom of 80 the apparatus.

At the upper end of the pipe 11 is an adjustable sleeve 13, which can be raised or lowered to vary the height of water in the inner compartment 14 between the inner casing 12 and the pipe 11. The sleeve 13 can be adjusted in any suitable manner. In the present instance, a spider 15 is shown, which is attached to the upper portion of the sleeve 13. The spider has a threaded opening 90 through which extends a screw threaded shaft 16, which is mounted in a bearing on the upper head 17. This shaft 16 is geared to an operating shaft 18 through a shaft 19 and gear wheels 20 and 21. On the operating shaft is a hand wheel by which the shaft can be turned. On the shaft is an indicator 22, which registers with a gauge plate 23 so that the operator can locate the sleeve 13 properly. In the upper end of the water compartment 14 are vertically arranged plates 24, which prevent the water swashing when the apparatus is used on a vessel.

In the lower end of the casing 2 are openings 25 that allow the water to pass from the upper channel 2 to the inner channel 14.

In order to keep a water level at all times, a water pipe 26 is provided, which com-

municates, in the present instance, with the lower end of the channel 3, Fig. 1. This pipe is connected to any suitable water supply so that a continuous flow of water is maintained at all times to insure a full water level in the apparatus and prevent the accidental flow of oil through the water pipe.

In the pipe 26 is a check valve 27, which prevents the back flow of water from the apparatus.

In order to prevent the passage of foreign matter, which is heavier than water, to the apparatus, a tank 28 is provided, which is located, preferably, above the apparatus, as shown clearly in Fig. 1. The outlet pipe 29 of this tank is connected to the inlet pipe 5 of the apparatus.

The water is admitted to the tank from the bilge pump, or ballast pump, through a pipe 30. Within the tank is a perforated partition 31 that forms a chamber 32 in which the heavier particles of material settle. The water and small particles pass through the perforated partition into the main chamber 33, in which are three partitions 34, 35 and 36. The partitions 34 and 36 act as weirs. The partition 35 extends from the top downwards between the partitions 34 and 36 so that the water and oil must travel in circuitous paths through the tank to the outlet pipe 29. Directly above this outlet pipe is an inclined perforated partition 37.

As the water and oil pass through the tank, any particles, heavier than water, accumulate in the bottom of the tank so that the water and oil are free of particles heavier than water when the mixture enters the main apparatus.

The operation is as follows: Bilge water, or ballast water, carries a certain amount of oil, which must be separated from the water before the water is allowed to flow overboard from the vessel. This apparatus is primarily intended to separate oil from water. The pumps also discharge a certain amount of foreign matter, which is heavier than water. This foreign matter is first separated from the oil and water to prevent clogging of the apparatus.

The water and oil after passing through the tank 28 pass into the channel 3 of the apparatus and flow down through the spiral passage to the bottom of the apparatus. As the water flows downwards, the oil rises to the surface of the water and travels upwards on the under side of the helical deflectors. The oil finally passes on one side of the vertical section 4 of the deflector and into the oil zone 6. The oil is preferably heated in this zone so as to flow freely from the apparatus through the discharge pipe 9. The water passes from the outer channel 3 through the openings 25 in the

bottom of the inner casing 2 and up the channel 14 to the upper end of the water discharge pipe 11, from which it flows to waste.

Should the flow of water be discontinued at any time, the water line of the apparatus is maintained by water flowing from the pipe 26, which forms a trap to prevent oil flowing overboard through the waste pipe 11.

It will be understood that my improved apparatus for separating water and oil may be used on land, as well as on a vessel, without departing from the essential features of the invention.

I claim:

1. The combination of an outer casing and an inner casing spaced apart forming an outer channel; a spiral deflector in the channel terminating in a vertical section that extends into the lighter liquid zone of the apparatus; a discharge pipe for the heavier liquid extending within the inner casing and terminating at the lighter liquid zone; an enlargement on the inner casing forming a lighter liquid zone; an outlet pipe for the lighter liquid at the upper end of said zone; and an inlet pipe for the liquids to be separated below the lighter liquid zone and on the upper side of the spiral deflector.

2. The combination of an outer casing; an inner casing forming an inner channel and an outer channel; an inlet passage for the liquids to be separated, said passage communicating with the outer channel; a pipe for the heavier liquids communicating with the inner channel, and an outlet for the lighter liquids in the upper end of the outer channel; vertically arranged plates extending into the upper end of the inner channel which prevent the liquid swashing when the apparatus is used on a vessel or other moving carrier.

3. The combination in an apparatus for separating liquids of different specific gravity, of an outer vertical casing and an inner casing forming an inner channel and an outer channel; a helical deflector in the outer channel, said deflector having a vertical section extending to the lighter liquid zone of the apparatus; an inlet pipe for the liquids to be separated communicating with the outer channel on the upper side of the deflector; a casing, forming an enlargement secured to the inner casing, and reducing the area of the light liquid zone and beveled on its underside, the enlargement having a vertical passage for the free flow of the lighter liquid; and a steam coil within the light liquid zone between the outer casing and the enlargement, the pipe being separated opposite the passage in the enlargement so as to provide an unobstructed passage.

THOMAS FISHER.
